UNITED STATES PATENT OFFICE

2,571,446

SHOE WITH ROLLED THROAT LINE

John Henkel, Baltimore, Md., assignor to Dixon-Bartlett Company, a corporation of West Virginia

Application July 31, 1947, Serial No. 765,181

3 Claims. (Cl. 36—45)

1

The object of this invention is to construct a double lined pump with a throat section which will not only retain the shoe snugly on the foot, but which will fit comfortably, and not bind.

Many efforts have been made to construct a padded or elastic throat section, but these have required the insertion of additional materials and at times additional layers of material. Other such efforts have suggested the slitting or weakening of the throat section, the slitting injuring the appearance and weakening the holding-on value of the throat section.

By this invention, no inserts or additional parts are required and the section is not weakened, rather the usual parts are so designed and disposed in the throat section as themselves to furnish a soft, round, pliable edge, free of lining, and yet a firm holding section over the instep of the foot is provided.

These and other objects and advantages will be apparent from the following descriptions and the accompanying drawings forming a part hereof, and in which:

Figure 1 is a plan view of the outer face of the forepart of a vamp upper assembly of the pump of this invention.

Figure 2 is an inverted plan view of the same.

Figure 3 is a sectional view in perspective on line 3—3 of Figure 1.

Figure 4 is a fragmentary inverted plan view of the vamp section with the middle lining attached.

Figure 5 is a similar view with the edge of the throat of the vamp section turned over, in fan formation.

Figure 6 is an inverted plan view of the inner lining.

Figure 7 is an enlarged cross sectional view on line 7—7 of Figure 1, looking in the direction of the arrows.

In the drawings similar numerals refer to similar parts throughout the several views.

The outer one-piece upper of the pump leather 1 is initially cut in extended or flat position with integral vamp and quarter sections with the edge 2 at the throat to give an arcuate final form and with the throat line 3 creased to indicate its location. The edge, well outside the throat line is skived on the inside of the leather as shown at 4 to bring the leather down to a thin wedge as shown at 5. This edge is then slit as at 6.

The intermediate or middle lining has quarter sections 7 extending down partly around the throat ends at 8 and a vamp section 9 terminating considerably short of the throat line 3 as shown at 10.

2

The extended edge 2 of the throat is then folded over the lining 7 and 9, in fan formation, as shown at 11 and cemented to the lining and this leaves a roll 12 at the throat consisting of two thicknesses of the leather which is itself particularly soft and pliable, and not being reinforced, it is slightly stretchable and rolls under pressure of the foot instep.

The inner lining has quarter sections 13 of leather stitched together at 14 and stitched to the fabric inner lining 15 well below the throat section as shown at 16.

A piping 17 is thereafter sewed by seam 22, around the edge of the shoe upper opening and 15 slightly over the extreme ends of the throat line roll 12 as shown at 18. This piping is then turned in around and under the edge of the opening, and stitched on through the middle lining and outer section as shown at 19. The inner lining

20 13 shown in Figure 6 is then placed on the outer section and middle lining 7, 9 and stitched at 20 all around the shoe opening. The stitching 20 passes around the throat, then up the sides of the opening so close to the turn in the piping

25 17 as to be scarcely visible, after leaving the throat. The throat 21 of the inner lining terminates considerably short of the throat line 3 of the vamp section to leave the roll 12 free of the rigidity of the linings. The edges 23 of quarter sections 13 are cut off at lines 24, see Figure 6, after the final line of stitching 20 attaches the inner lining to the upper 1.

From this construction it will be apparent that the rather rigid form of the shoe throat beginning with the stitching 20 at the edge of the inner lining at the throat 21 firmly retains the shoe upon the wearer while the relatively resilient roll 12 of the outside vamp section makes the first contact with the rising portion of the instep of

40 the wearer and pads the foot against the more rigid portion of the shoe and considerably eases the impact of the shoe upon the foot while the more rigid portion securely holds the shoe in place.

45 Roll 12 forms a continuous marginal contour, uncut and unpadded and makes a very neat appearance with the rest of the shoe, being a plain inturned edge of both great strength and resilience, being unreinforced and also unweakened 50 at the throat line and considerably beyond over that line. The bringing of the piping beyond the ends of the throat line reinforces that line where it joins the rest of the vamp section to considerably restrict any deformation of that line at its ends.

Many modifications of the present invention

will be apparent to those skilled in the art without departing from the spirit of the invention as defined in the appended claims.

What is claimed as new and is desired to be secured by Letters Patent is:

1. A shoe comprising an upper having integral vamp and quarter sections, the vamp section having an edged portion arranged to provide a resilient arcuate throat line, the edge of the vamp portion forming the throat line being slitted and turned under, the slits terminating well short of the throat line, a middle lining extending along each side of the upper quarter sections and having ends on each side extending under the in-turned edge of the throat and terminating thereunder adjacent the ends of the throat line, the edge of the vamp portion, between the ends of the middle lining, being folded under directly upon itself to form a thin throat, the slitted edge fanning out, in fan formation, an inner lining for the upper cut to provide a throat substantially lower than and parallel to the throat line of said vamp section, said last named lining underlying the slitted edge of the vamp section and a seam spaced from the throat line passing through the vamp section, the middle lining and the slitted edge and uniting the vamp and inner lining below the throat line, the seam and linings limiting the extent of the individual resilience of the single fold of the vamp section, the vamp section thereby forming a firm, freely mobile, smooth arcuately continuous surfaced roll at the throat line.

2. A shoe comprising an upper having integral vamp and quarter sections, the vamp section having an edged portion arranged to provide a resilient throat line of continuous marginal contour, the edge of the vamp portion to form the throat line being skived and turned under, the skiving terminating well short of the throat line, a middle lining extending along each side of the upper quarter sections and having ends on each side extending under the in-turned edge of the throat and terminating thereunder adjacent the ends of the throat line, the edge of the vamp portion, between the ends of the middle lining being folded under directly upon itself to form a thin throat, an inner lining for the upper cut to provide a throat line substantially lower than and parallel to the throat line of said vamp section, said last named lining underlying the skived edge of the vamp section and a seam spaced from the throat line passing through the vamp section, the

5 middle lining and the skived edge and uniting the vamp and inner lining below the throat line, the seam and linings limiting the extent of the individual resilience of the single fold of the vamp section, the vamp section thereby forming a firm, freely mobile, arcuately continuous surfaced roll at the throat line.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

3. A shoe comprising an upper having integral vamp and quarter sections, the vamp section having an edged portion arranged to provide a resilient throat line of continuous marginal contour, the edge of the vamp portion to form the throat line being skived and turned under along the throat line directly upon itself at the line of fold to form a thin throat, the skiving terminating well short of the throat line, an inner lining for the upper cut to provide a throat substantially lower than and parallel to the throat line of said vamp section, said lining underlying the skived edge of the vamp section; a seam spaced from the throat line passing through the vamp section, the skived edge and uniting the vamp and lining below the throat line, a piping extending along the edge of each quarter section of the upper and extending to and over each end of the throat line to grip the portion of the upper forming the throat line, the seam, piping and lining limiting the extent of the individual resilience of the single fold of the vamp section, the vamp section thereby forming a firm, freely mobile, smooth, continuous marginal surfaced roll at the throat line.

JOHN HENKEL.
